UNITED STATES PATENT OFFICE.

SAMUEL CHANDLER, SR., SAMUEL CHANDLER, JR., AND JOSIAH CHANDLER, OF LONDON, ENGLAND, ASSIGNEES TO KIRKHAM, HULETT & CHANDLER, (LIMITED,) OF SAME PLACE.

APPARATUS FOR WASHING AND SCRUBBING GAS.

SPECIFICATION forming part of Letters Patent No. 406,124, dated July 2, 1889.

Application filed February 6, 1889. Serial No. 298,841. (No model.)

To all whom it may concern:

Be it known that we, SAMUEL CHANDLER, Sr., SAMUEL CHANDLER, Jr., and JOSIAH CHANDLER, subjects of the Queen of Great Britain, and residents of London, England, have invented new and useful Improvements in Apparatus for Washing and Scrubbing Gas, of which the following is a specification.

This invention relates to improvements in the washing and scrubbing of gas and to the scrubbing devices used therefor.

According to our invention, we cause liquor from the last or foulest bay of a washer-scrubber to be carried back to a bay or bays through which the liquor has already passed, whereby we thoroughly extract the ammonia from the gas and increase the strength of the ammoniacal liquor and more effectually than heretofore purify the gas from other impurities.

Our invention, in so far as it relates to scrubbing devices used for providing wetted surfaces in washer-scrubbers, consists in providing scrubbing devices, as hereinafter more particularly described, which shall be simple, effective, light, and economical, and adapted to rotate in the bays or receptacles of a washer-scrubber.

To enable our invention to be fully understood, we will describe how it can be carried into practice by reference to the accompanying drawings, in which—

Figure 1 is a side elevation of a gas washer-scrubber constructed according to our invention. Fig. 2 is a plan, partly in section, of the same; and Fig. 3 is a vertical section on the line A B of Fig. 1. Fig. 4 is a detached end view, drawn to an enlarged scale, of one of the sections of our improved scrubbing devices, and Fig. 5 is a section of the same on the line C D of Fig. 4. Fig. 6 is a transverse vertical section of part of a wheel formed by our scrubbing devices; and Fig. 7 is a side elevation of the same, partly in section, on the line E F of Fig. 6. Figs. 8, 9, 10, and 11 are corresponding views to those shown in Figs. 4, 5, 6, and 7, illustrating a modification of the arrangement of the scrubbing devices, a is the body or casing of the apparatus.

which is divided into bays or chambers containing water or other suitable liquid, (the level of the liquid in the said chambers being successively lower from one end to the other of the casing.) b is a shaft mounted in the casing for carrying revolving scrubbing devices adapted to be maintained in a wet condition by passing through the water or other liquid in the chambers; and c c c' c' are the gas inlets and outlets, respectively. All the said parts are of well-known construction, being substantially the same as described in the specification of Patent No. 206,736, dated the 6th day of August, 1878, and therefore need no further description.

d is one of the scrubbing devices mounted on the shaft b, and constructed as hereinafter described.

e e are buckets secured to the side of the scrubbing device in the chamber containing the liquid at the lowest level.

f is a trough upon the inner side of the casing a, adjacent to the said buckets, and g is a pipe extending from the said trough to all the other chambers, so that as the liquid is raised by the buckets and discharged into the trough it will flow into the several chambers.

h h are cocks by means of which the liquid can be shut off from any chamber or chambers, as desired.

The surfaces of the scrubbing devices d are advantageously composed of wood bars i in the form of plasterers' laths, although bars or laths of any other suitable material may be employed. These bars are carried between side plates j j' j', of preferably segmental shape, which plates j' j' are slotted to receive them, as shown in Figs. 4 and 5, the slots being advantageously arranged, so that the laths of one layer come opposite to the spaces between the laths of the next layer, and vice versa.

The segmental sections thus formed are secured to a wheel k between disks l l', as shown in Figs. 6 and 7, so that they will rotate with the central shaft b.

We sometimes modify the construction of the sections, as shown in Figs. 8 and 9, by dispensing with the side plates j j' j'. In such case transverse laths m m are placed be-

tween the layers of laths *i i* to maintain them at proper distances apart, the ends of the sections being bound with hoop-iron to hold the laths in their proper relative positions. These 5 sections are secured to a central wheel between side plates of the kind hereinbefore described by means of bars *n n* and bolts *n'*, as shown in Figs. 10 and 11; but they may be secured by any other desirable means.

- 10 By our improved construction of scrubbing devices it will be obvious that the gas, as it travels through the scrubber, is split and broken up in a more advantageous manner, and a more zigzag course is given to it than 15 hitherto, whereby it is brought into very intimate contact with the wetted surfaces of the scrubbing devices and is subjected to a very effectual combing, which greatly facilitates the extraction of the tar and other impurities.
- 20 Our improved apparatus requires relatively but little power for driving it, and the wear and tear is inconsiderable.

Having now particularly described and ascertained the nature of our said invention 25 and in what manner the same is to be performed, we declare that what we claim is—

1. In apparatus for washing and scrubbing gas, the combination of one or more buckets secured to the side of a revolving scrubber, 30 with a trough on the inner side of the casing, and into which the said bucket or buckets is or are adapted to discharge, the said trough being suitably connected by a pipe or channel with one or more of the bays or chambers 35 of the apparatus, substantially as and for the purpose hereinbefore described.
2. In apparatus for washing and scrubbing gas, comprising a number of bays or chambers, as set forth, a series of scrubbing

devices, each of which is essentially constructed of a number of sections built up of bars or laths carried between suitable side plates and disks, or disks alone, the bars of one layer being disposed opposite the spaces of the next adjacent layer, and whereby, as 45 the scrubbing devices rotate, a large area of wetted surface is provided, and whereby a very zigzag course is given to the gas in passing through the apparatus, the gas being thereby thoroughly broken or split up and brought 50 into very intimate contact with the said wetted surfaces, substantially as described.

3. Scrubbing devices for machines for washing and scrubbing gas, adapted to be mounted on a rotary wheel and severally composed of 55 a series of laths or bars disposed with those of one layer opposite the spaces of the next adjacent layer, as shown and described, and secured to and carried between segmental side plates slotted to receive them.

4. The combination, with the casing having a series of chambers, of revolving scrubbers having segmental sections and having buckets secured to their sides, a trough on the inner side of the casing, a pipe extending 65 from said trough to the several chambers, and cocks adapted for shutting off the liquid from any one of the chambers, the bars of the scrubber being slotted side plates, and those of one layer being placed opposite the 70 spaces existing between the bars of the next adjacent layer, all substantially as set forth.
